UNITED STATES PATENT OFFICE.

CARL F. NILSON, OF GILE, WISCONSIN.

BICYCLE.

SPECIFICATION forming part of Letters Patent No. 605,331, dated June 7, 1898.

Application filed June 21, 1897. Serial No. 641,732. (No model.)

To all whom it may concern:

Be it known that I, CARL F. NILSON, a citizen of the United States, residing at Gile, in the county of Iron and State of Wisconsin, have invented certain new and useful Improvements in Bicycles; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in bicycles; and the object of my invention is to provide a bicycle adapted for riding on a single rail laid for that purpose or on one of the rails of any common railroad-track. I attain this object by the novel construction and arrangement of parts illustrated in the accompanying drawings, in which—

Figure 1 is a side elevation of my bicycle in a simple form shown as standing on a piece of rail laid upon ties on the ground. Fig. 2 is a top view of Fig. 1, with the rider's seat and seat-holder removed. Fig. 3 is a top view of the frame and steering mechanism, showing modifications or further improvements in the last-named parts. Fig. 4 is a cross-section 30 of the frame as on the line *aa* in Fig. 1, looking forwardly.

Referring to the various parts in the drawings by letters of reference, A designates the ground, B the ties, and C the rail upon which ride in line the two grooved carrier-wheels D and E, which have their shafts F and G journaled in and carry the elongated frame H, from which extends upwardly the frame portion I, (best shown in Fig. 4,) which in its top 35 carries the rider's seat J and near its top the forwardly-extending arm K, supported by the brace L and having journaled in it at M the steering-rod N, provided at its top with the handles O and having its lower end journaled at P in the front end of the frame H, and is below said frame provided with a horizontally-swinging arm Q, carrying two guiding sheaves or rollers R, engaging both sides of the rail. The rear end of the frame is provided 40 with two downwardly-extending arms S, carrying similar guiding-rollers T for guiding the rear end of the frame always in about

central line with the rail, while the front end of the frame may be thrown from side to side by the handles O, rod N, and the sheaves R, 55 so as to balance the machine and the rider. In order to allow the frame to be thus thrown or moved horizontally from side to side, I allow the shaft F to slide either in the front wheel D or in the side bars of the frame H, 60 as the maker may prefer.

The above-described arrangement is suited for a cheap grade of bicycles, while for a better grade I use the modification shown in Fig. 3, in which it will be seen that the lower 65 end of the steering-rod N is provided with a lever forming two arms U, which are connected by the rods V to the arms W of a two-armed lever X, pivoted at its center Y to the rear end of the frame H, and is provided with 70 two rearwardly-extending arms Z, carrying the guide-rollers T T, one at each side of the rail, while the front lever U U is provided with two similar arms b, carrying the rollers R, one at each side of the rail, so that by 75 turning the steering-rod N slightly to one side or the other the entire bicycle-frame and its rider are all moved in the horizontal plane beyond the center of the rail, and by thus changing the center of gravity from side 80 to side the rider balances the bicycle while propelling it forward by the foot-cranks d, large chain-wheel e, belt-chain f, small chain-wheel or pinion g, shaft G, and carrier-wheel E, which serves as traction-wheel for the 85 machine.

When the steering mechanism is complete, as in Fig. 3, the two shafts F and G must slide either in their respective wheels or in the journals in the frame H, and if the latter 90 method is employed I prevent the pinion g from sliding by having an annular groove in its hub l, engaged by a guide k, secured on the frame. The wheel e is of course secured on the crank or treadle shaft m.

In the drawings but little space is shown for the sidewise moving of the frame; but in making the machines all necessary play is given between the frame and the sides of the carrier-wheels.

I am aware that the belt-chain f may be dispensed with and the wheel e and pinion g be made spur-gears, meshing and driving the larger the smaller one, and that many

other changes may be made without diverging from the spirit of my invention.

What I claim as new, and desire to secure by Letters Patent, is—

- 5 1. A bicycle having grooved ground-wheels adapted to ride on a rail, a frame supported by said wheels and having horizontal motion to either side, guiding-rollers mounted on horizontally-swinging arms and touching the sides of the rail, said arms being operatively connected with a pair of handles within easy reach of the rider, substantially as and for the purpose set forth.
- 10 2. In a bicycle, the combination of a suitable frame, a pair of grooved ground-wheels carrying same, and being adapted to run on

a rail and having lateral motion in direction of their shafts, a crank-shaft mounted in the frame and geared to one of the ground-wheels, a seat for the rider, mounted on said frame, a pair of handles for the rider to have hold of and horizontally-swinging arms operated by said handles and carrying guide-rollers adapted to touch the sides of the rail and throw the frame from side to side, substantially as and for the purpose set forth. 20 25

In testimony whereof I affix my signature in presence of two witnesses.

CARL F. NILSON.
